UNITED STATES PATENT OFFICE.

CHRISTIAN HUBERT MARTIN, OF ATLANTA, GEORGIA.

ORTHOPEDIC APPLIANCE.

Application filed March 28, 1922. Serial No. 547,536.

To all whom it may concern:

Be it known that I, CHRISTIAN HUBERT MARTIN, a citizen of the German Republic, residing at Atlanta, in the county of Fulton and State of Georgia, have invented a new and useful Improvement in Orthopedic Appliances, of which the following is a specification.

This invention relates to orthopedic appliances and particularly to an improved connection between an orthopedic joint and a brace bar.

An object of the invention is to provide such a connection as will allow an exact fitting of a leg or arm brace to any individual, and ready replacement of a brace with another of greater length, as when the wearer outgrows the original appliance. There are various other objects which will become apparent from the following description.

In the accompanying drawings, wherein are shown preferred embodiments of the invention by way of illustration,

Figure 1 is an elevation showing a human limb provided with an orthopedic appliance made in accordance with my invention;

Figure 2 is a fragmentary view of a leg brace showing the joint in elevation and one of the bars removed from the joint;

Figure 3 is a longitudinal section through the parts of Figure 2;

Figure 4 shows one of the bar ends in perspective;

Figure 5 is a transverse section on the line 5—5 of Figure 2 but on a larger scale;

Figure 6 is a transverse section through a connection between a modified form of bar and a joint, the view being similar to Figure 5;

Figures 7 to 14 are views of various joints adapted for different uses but all embodying the improved construction of my invention.

Referring more specifically to the drawings and to the illustrative embodiments of the invention there shown, a joint member 15 is connected in any preferred way, as by a rivet, screw, or bolt 16, or by brazing, to a bar 17 at each end. It is preferred that the bar 17 be transversely curved as seen in Figure 4, and that the longitudinal edge portions of the bar be flat, so that the bar 17

presents a longitudinal concave channel. Such a construction is strong and yet light in weight. It is absolutely necessary, however, that these bars, whatever their shape, be uniform in cross section to realize fully the advantages of this invention.

The joint member 15 is slotted at each end to receive the ends of two bars 17, and the slots 18 are shaped to make a nice fit for the bar ends. The slots 18 extend longitudinally of the joint members so that the ends of said members are bifurcated, one of the furcations 19 preferably being in the form of a tongue narrower than the joint member 15, and adapted to fit within and against the concave side of bar 17. The other furcation 20 is preferably concavo-convex, and has the full width of the joint, with edges 21 adapted to fit the flat edge portions of bar 17, as shown in Figure 5. The slots 18 extend but a relatively short distance along the bar ends and are curved to correspond with the bar.

The face of the furcation 19 opposite the curved face is flat, and when the joint is fitted to the bar end, the said flat face is flush with the flat edge portions of said bar (Figure 5). Near one end of each bar 17 a hole 22 is drilled so that the fastening element 16 may be passed through said hole and registering holes 23 in the furcations 19 and 20, as shown in Figures 2, 3 and 5. Because of the nice fit between the joint member 15 and the bar end, which is due to the conformity of the slots 18 to the exact cross section of bar 17, a single fastening element 16 serves to hold the bars to the joint member without any wobbling or loose motion. The connection is such that for all practical purposes the bars 17 are of one piece with the joint members; yet the parts may be separated when desired.

Figure 6 shows a transverse cross section of a modified bar 17^a which is concavo-convex without any longitudinal flat edge portions as in Figure 4. The slot 18^a, tongue 19^a and furcation 20^a correspond to the slot 18, tongue 19 and furcation 20, there being slight alterations in the form of each to make an exact fit with bar 17^a.

In Figures 7 and 8, I have shown respectively an elevation and a longitudinal section of a joint member allowing limited motion of an ankle, knee, etc. Figures 9

- and 10 show in elevation joints constructed to stop ankle motion at a certain position. Figure 11 is a longitudinal section of a knee joint which allows free bending at the knee.
- 5 In each form the bar 17 fits exactly the recess provided by slot 18.
- Figures 12, 13 and 14 show a lock joint, intended primarily for knees. Figure 12 is an elevation illustrating the joint locked.
- 10 Figure 13 is a longitudinal section of the parts in the position of Figure 12. The joint is shown unlocked in Figure 14. In order to lock the pivoted parts of the joint member, a slip ring 25 is provided. When
- 15 the ring 25 is moved down so as to enclose the two pivoted parts of the joint member, these parts may no longer swing, so that the leg is held rigid, as for walking. If the wearer desires to sit down, ring 25 is moved
- 20 up about to the position shown in dotted lines in Figure 12, whereupon the joint members may be turned, and the ring will then fall to the position shown in Figure 14.
- By utilizing the present invention, a manufacturer of orthopedic devices may make leg and arm braces faster and more economically than before, and these braces will be lighter and more comfortable. Formerly, the braces had to be made on
- 25 separate orders to fit each individual, and it often happened that through a mistake in measurement the bar would be too long or too short, and would have to be discarded. If such a bar were used it would always
- 30 bring discomfort to the wearer and would make the joint move harder than it should. Again, with old style appliances, when the limb grows the appliance must be discarded for a larger one. As the wearer
- 35 grows, ankle or knee joints demand more clearance sideways, causing a lengthening or shortening of the bar, thereby bringing the joint out of a horizontal bearing line, causing hardship to the wearer. But with
- 40 the present invention, the bars 17 can be removed if too long and cut to any length desired, if necessary, while the lame wearer waits. A longer bar of exactly the right length may be substituted for a shorter bar
- 45 in a few minutes, and the longer appliance may be adjusted accurately. The bars 17 will be standardized, so that one which has been used but discarded because too short, for example, can be fitted into joint members to form another appliance. Because of
- 50 the uniform cross section of the bars, any one may be cut down as much as necessary and still make a nice fit with the joint member.
- 55 In many cases of infantile paralysis the patient uses stop joints at the ankles and a locking joint (Figures 12, 13 and 14) at the knees and hips. Probably after one or two months activity the muscles have sufficiently
- 60 developed so that the patient can be al-
- lowed more freedom of his limbs. By the old style apparatus it was necessary to make new bars or braces with differently constructed joints, which of course was expensive. My invention permits the substitution of one joint for another, using the same brace bars as before, if desired.
- Instead of using rivets, bolts or screws as fastening means between the joints and the bars, the parts may be fitted together by
- 65 brazing. I have not attempted to illustrate this because it is not susceptible of exact disclosure, but I wish it understood that my invention comprehends this as a means for uniting the bars and joints.
- 70 While I have described certain embodiments of the invention, it will be understood that changes involving alteration, omission, reversal and substitution of parts may be made without departing from my invention, which is best defined in the following claims.
- 75 What is claimed is:
1. In an orthopedic appliance, the combination of a joint member and a brace bar, said joint member being slotted at one end in a longitudinal direction to receive one end of the brace bar which is inserted in and fills the slot of the joint member, and means
- 80 uniting the bar to the member, said bar being of uniform cross section throughout its length. 90
2. In an orthopedic appliance, a joint member having a slot extending longitudinally from one end, said slot bifurcating the end of the member so as to provide a tongue of less width than the member, and a furcation of the full width thereof, the slot being shaped to receive and make a nice fit with a brace bar. 100
3. In an orthopedic appliance, a joint member having a transversely curved slot extending inwardly in a longitudinal direction from one end, said slot bifurcating said end so as to provide a tongue of less width than the member, and a furcation of substantially the full width thereof. 110
4. In an orthopedic appliance, the combination with a bar substantially of uniform concavo-convex cross section throughout its length, of a joint member slotted at one end longitudinally to receive an end of said bar, said slot bifurcating the member end so as to provide a tongue adapted to fit within the concave side of the bar, and also providing a furcation adapted to fit the convex side of the bar, and means passing through holes in the bar end and joint member transversely to hold the two parts together and yet permit detachment. 115
5. In an orthopedic appliance, the combination with a bar substantially of uniform concavo-convex cross section throughout its length, with the longitudinal edge portions flat, of a joint member slotted at one end
- 120
- 125
- 130

longitudinally to receive an end of said bar, said slot being transversely curved and bifurcating the end of the member so as to provide a tongue adapted to fit substantially

5 flush within the concave side of the bar, the outer face of the tongue being flat, and also providing a furcation adapted to fit the con-

vex side of the bar with its edges engaging the flat longitudinal edges of the bar, and means for uniting the bar and joint member. 10

In testimony that I claim the foregoing as my own, I have hereto affixed my signature.

CHRISTIAN HUBERT MARTIN.
